UNITED STATES PATENT OFFICE

KIRBY SHARP, OF ODEM, TEXAS

RAIL JOINT

Application filed July 9, 1929. Serial No. 376,958.

This invention relates to improvements in means for connecting the ends of railway rails, and the object thereof is to form the abutting ends of adjacent rail lengths in such a manner that will assist the fish plates in sustaining the heads of the rails against vertical movement, prevent pounding of the wheels of a railway car upon the meeting ends of the rails and to provide a rail joint that shall be safer than the joint usually employed.

With the above and other objects in view, the improvement resides in the construction, combination and arrangement of parts set forth in the following specification and falling within the scope of the appended claim.

In the drawing, Figure 1, is an elevational view showing the abutting ends of two adjacent rails in spaced relation.

Figure 2 is a plan view of the joint proper. The rails 1 and 2 are of the conventional T-form and comprise treads 3 and 3', webs 4 and 4' and bases 5 and 5'. To form the joint, both of the rails 1 and 2 have their ends cut and shaped as follows:

The tread 3 and web 4 of the rail 1 are cut vertically downward in a plane at any suitable angle to the longitudinal axis of the rail, the angular cut terminating at the exact bottom of the web 4 or the top of the base 5, said end of the cut being designated by 6; the same being true of the rail 2. The bases 5 and 5' are then cut through in a plane at right angles to the longitudinal axis of each of said rails. It is to be distinctly noted that the transverse plane of the cut through the bases 5 and 5' coincides with the edges 7 and 7' of the rear side of the webs 4 and 4', i. e. (looking at the rails 1 and 2 from the position shown in Figure 1). In other words the plane of the transverse cut and the plane of the angular cut intersect at the point A (Figure 2) which point is the upper terminus of a line common to both abutting surfaces of the rails 1 and 2.

The rails 1 and 2 are joined together by the conventional fish plates 8 and 9 and rivets or bolts 10.

Having thus described the invention, what I claim is:

In a rail joint, rail sections, each of said rail sections having its base portion cut at a right angle to the length of the section, the cut portion extending straight from one edge of the base of the rail to the opposite edge, 55 the tread of each rail section having a diagonal cut, said diagonal cut extending through the web and crossing the straight cut in the base, the diagonal cut on one rail meeting the straight cut on that rail at a point coinciding with the near side of the web to the acute angle of the diagonal cut in said rail, and the diagonal cut on the other rail meeting the straight cut at a point coinciding with the far side of the web to the acute angle of the diagonal cut on that rail.

In testimony whereof, I affix my signature.

KIRBY SHARP.
